UNITED STATES PATENT OFFICE.

THOMAS LEVI, OF NEW WESTMINSTER, BRITISH COLUMBIA, CANADA.

DEVICE FOR KEEPING FISH, MEAT, FRUIT, AND OTHER PRESERVING CANS CLEAN WHILE BEING FILLED.

SPECIFICATION forming part of Letters Patent No. 296,023, dated April 1, 1884.

Application filed March 12, 1883. (No model.)

To all whom it may concern:

Be it known that I, THOMAS LEVI, of the city of New Westminster, in the district of New Westminster and Province of British Columbia, Canada, carpenter, have invented a new and useful Improvement for Keeping Fish, Meat, Fruit, and other Preserving Cans Clean While Being Filled, of which the following is a specification.

10 My invention is a tin case or cylinder to fit over fish, meat, fruit, or other preserving-cans while being filled, so that the person filling the same need not touch the cans with his hands. The tin case or cylinder is made one 15 size larger in circumference at the top, increasing in size to the bottom, and a size shorter in length than the preserving-can, with a rim at the top turned inward and downward. When the preserving-can is filled, 20 it is lifted by the pressure of the fingers and thumb on the case or cylinder until it touches the preserving-can inside, the object of my invention being to keep the can while being

filled clean, and to enable the person filling the preserving-can to remove it after it has 25 been filled without touching the preserving-can with his hands, and thereby keep it clean and save labor.

Figure A is the preserving-can. Fig. B is the case or cylinder for keeping the preserving-can clean. Fig. C is the preserving-can covered with the case or cylinder. Fig. D is 30 a section of the preserving-can and case or cylinder.

I make no claim to the preserving-can A; 35 but

What I claim is—

The combination of the case or cylinder B with the preserving-can A, when applied as shown in the Fig. C, substantially as de- 40 scribed.

THOMAS LEVI.
